UNITED STATES PATENT OFFICE.

WILLIAM J. SMITH, OF BROOKLYN, NEW YORK.

MAIL-BAG DELIVERER.

No. 833,643.

Specification of Letters Patent.

Patented Oct. 16, 1906.

Application filed July 18, 1906. Serial No. 326,766.

To all whom it may concern:

Be it known that I, WILLIAM J. SMITH, a citizen of the United States of America, residing at Brooklyn, in the county of Kings and State of New York, have invented new and useful Improvements in Mail-Bag Deliverers, of which the following is a specification.

This invention relates to mail-bag projectors or deliverers, the object of the invention being to provide a simple and effective device or apparatus for delivering a pouch, parcel, or package without injury to a passing car and which is thrown into operation by an actuating element on the car.

In the accompanying drawings, Figure 1 is a perspective view showing the device set for operation and about to be tripped by the trip member on the car. Fig. 2 is a vertical longitudinal section through the device and a fragmentary transverse section through the car, showing the parts in operative position, the projected positions of the operating members of the deliverer being indicated in dotted lines. Fig. 3 is a detail showing the means for supporting the striker in elevated position. Fig. 4 is a section through the striker-head.

The device comprises a supporting-frame 1, which may be of any preferred construction. As shown in the present instance, the frame is of oblong rectangular form and comprises corner-standards 2, side standards 3, top and bottom side and end rails 4 and 5, connecting said standards, and a central transverse cross-brace 6.

Journalized in the side standards 3 is a shaft 7, to which is fixed a delivery-lever 8. This lever is provided with front and rear arms 9 and 10, the front arm being provided at its free end with a contact portion 11, adapted to be engaged by the striker hereinafter described, while the arm 10 is provided with a receptacle 12 to hold the pouch or other article to be delivered to the car. The receptacle 12 is in the form of a spoon-shaped holder, operating as a weight to normally adapt the lever to assume a substantially horizontal position by gravity, the holder 12 resting in such position upon the rear upper rail of the frame.

The standard 3 at one side of the frame and the adjacent front corner-standard 2 are provided with upward extensions 13, forming bearings for a rock-shaft 14, which carries a striker comprising an arm 15 and a head 16 affixed thereto, said head being preferably

in the form of a weighted ball, which is adapted upon its descent to engage the contact portion 11 of the lever, thus throwing the arm 9 of the lever downward and the arm 10 upward, whereby the bag or pouch 17, resting in the holder 12, will be thrown forward into the passing car through the doorway in the side thereof. Buffer-springs 18 and 19 are provided to yieldingly arrest and cushion the downstroke of the arm 9 and striker-head 16. The head 16 has a flattened outer face provided with a cushioning-strip 20, and is adapted to be supported in its elevated operative position by a lug 21 on one end of the shaft 14, which contacts with a lug 22 on the corner-standard, whereby the striker will be held tilted outwardly slightly beyond the perpendicular.

The car 23 carries an actuating device in the form of a trip-arm 24, which extends laterally therefrom and is adapted to engage the cushioned face 20 of the striker-head, so that the motion of the car will throw the striker forward, whereby it will descend under the impact as well as its own weight, and thereby forcibly strike and tilt the projecting lever to throw the bag or pouch into the car. A stay 25 of suitable construction is provided upon the car to reinforce the trip-arm when the latter comes into engagement with the striker. The trip-arm 24 is carried by a rock-shaft 26, journaled in a bearing extending through the floor of the car and provided at its upper end with a foot or hand lever 27, whereby said shaft may be swung to project or retract the arm, the latter being stayed when in operative position by the member 25. A roller or suitable support 28 is provided upon the shaft to rest upon the car-floor and hold the shaft from downward movement in its bearing.

It will be understood that in practice the actuating device is arranged a sufficient distance in advance of the door of the car in the direction of travel of the latter to insure the proper operation of the apparatus to project the sack through the door into the car as the train travels past the mail-station.

The device is set for operation in the manner shown in Fig. 1, and as the car passes the mail-station the arm 24 engages and swings the striker to effect the delivery of the pouch in the manner set forth. After operation the projecting lever automatically returns to normal position under the greater weight of its arm 10 after the trip has been swung up

on its shaft and reset for further use. It will be seen that the device is thus adapted to deliver the pouch, bag, or package to the car in an effective manner and without liability 5 of injury thereto, such as occurs by the use of catchers of ordinary construction in which the bag is forcibly torn from a crane by a catcher-arm on the car.

Having thus described the invention, what 10 is claimed as new is—

1. A mail-bag deliverer comprising a supporting-frame, a tilting bag supporting and impelling device carried thereby, and a striker operating by gravity when tripped to 15 forcibly strike and tilt said supporting and impelling device.
2. A mail-bag deliverer comprising a supporting-frame, a tilting bag supporting and impelling device, said device being pivotally 20 mounted on the frame, a weighted striker adapted to be tripped and to swing by gravity into contact with said supporting and impelling device to effect the tilting of the same, and means for normally supporting said gravity-striker in position to be tripped.
- 25 3. A mail-bag deliverer comprising a sup-

porting-frame, a projecting lever pivotally mounted on the frame and having operating and supporting arms, the latter being provided with means for holding a mail-pouch, 3 and a weighted striker adapted to be actuated by a passing car to engage the operating-arm of the lever and swing said lever on its fulcrum to impel the bag.

4. A mail-bag deliverer comprising a sup- 3 porting-frame, a pivotally-mounted bag holding and impelling device carried thereby, and a pivotally-mounted striker having a weighted striking-head adapted to engage and swing said lever on its fulcrum to impel 4 the bag.

5. A mail-bag deliverer comprising a sup- porting-frame, an impelling-lever carried thereby, a weighted striker for actuating the impelling-lever, and means for cushioning the lever and striker on their impelling action.

In testimony whereof I affix my signature in presence of two witnesses.

WILLIAM J. SMITH.
